UNITED STATES PATENT OFFICE.

OTTO KRAUS, OF NEW YORK, N. Y.

DESIGN FOR A NECKTIE-FASTENER.

SPECIFICATION forming part of Design No. 34,961, dated August 20, 1901.

Application filed July 3, 1901. Serial No. 67,043. Term of patent 7 years.

To all whom it may concern:

Be it known that I, OTTO KRAUS, a citizen of the United States, residing in the borough of Manhattan, in the city and State of New York, have invented and produced a new and original Design for a Necktie-Fastener, of which the following is a specification.

The subject of the present invention is a new and original design or configuration for a necktie-fastener.

The prominent or conspicuous features of the said design are embodied in a length or section of wire presenting a spring-eye open on one side, a tongue with a closed end, the tongue arranged behind the spring-eye and the closed end located opposite the open side of the eye, and a pair of arms on each side of said eye and tongue, one of said arms extending in a plane to the rear of the other.

In the accompanying drawings, forming part of this specification, Figure 1 is an elevation of a necktie-fastener embodying my new and original design. Fig. 2 is a side view thereof, and Fig. 3 is a plan view of the same.

As shown, a single piece or length of wire is configurated to present the eye or button-engaging portion *a*, open on one side *b*, a tongue *c*, with a closed end *d*, being also present and arranged behind the spring-eye with its closed

end opposite the open end of the eye, and a pair of arms *e f* on each side of said eye, one of the arms *f* of each pair being in a plane to the rear of its companion arm *e*. In the representation, however, of the new and original design for a necktie-fastener the lower end of the tongue is shown as oppositely bent or beveled, as indicated at *g*. The arms *e* are each also shown as having a lateral bend or offset *h*. It will also be noted that the portions presenting the eye *a* stand at an inclination relative to the vertical plane occupied by the arms *e*, and hence there is a wider connection between said portions and said arms at their base than occurs between the juncture of said portions with the spring-tongue.

Having now described my invention, what I claim as new, and desire to secure by Letters Patent, is—

The design for a necktie-fastener as herein shown and described.

In testimony whereof I have hereunto signed my name in the presence of the subscribing witnesses.

OTTO KRAUS.
